UNITED STATES PATENT OFFICE.

JOHN R. SIEBRANDT, OF KANSAS CITY, MISSOURI.

ARM SPLINT.

Application filed June 30, 1924. Serial No. 723,174.

This invention relates to arm splints and my object is to produce a splint which is universal in its adjustments to accommodate all possible positions of the arm including 5 the position of the upper arm using its longitudinal axis as the center of rotation and is suited for use with either the right or left arm.

Another object is to provide means whereby extension may be secured regardless of the position of the arm.

A further object is to produce an extension which is constructed practically entirely of aluminum and, therefore, does not interfere with the use of the X-ray.

A still further object is to produce a splint of the general character outlined which is mechanically simple and is of strong and durable construction and in order 20 that it may be fully understood, reference is to be had to the accompanying drawing, in which:—

Figure 1 is a view showing the use of the splint with the forearm extending vertically upward and the upper arm projecting horizontally outward to the side.

Figure 2 is a view similar to Figure 1, but with the forearm in the same horizontal plane as the upper arm and forming a right 30 angle therewith, a plaster cast on the body of the wearer and a different type of hand grip.

Figure 3 illustrates the forearm in supinated position with the same type of hand grip as illustrated in Figure 1.

Figure 4 illustrates the forearm and traction plate member for use in the extension of the upper arm when a fracture occurs in close proximity to the elbow and it is impossible or undesirable to employ adhesive traction means.

Figure 5 is a central section taken through the splint as it appears in Figure 1.

Figure 6 is an enlarged section on the 45 line VI—VI of Figure 5.

Figure 7 is an enlarged section on the line VII—VII of Figure 5.

Figure 8 is a central section taken through the hand grip employed in varying the angular position of the wrist.

Figure 9 is a bottom plan of the attachment shown in Figure 8.

In the said drawing, where like reference characters identify corresponding parts in 55 all of the figures, 1 indicates a body tubular member pivotally mounted at one of its ends

between a pair of ears formed on a bracket 2 securely fastened in any suitable manner to a body belt 3 provided with a suitable internal stiffening plate 4. The upper end of 60 the tube 1 is telescopically received within the open end of a second body tube member 5, which is split slightly at its lower end as at 5^a, and is formed with a pair of clamping ears 6 engaged by a clamping bolt 7, 65 whereby said member may be clamped in any desired position of vertical or rotary adjustment relative to the tube 1. The body of the patient is encircled by a second belt 8 provided with an internal stiffening member 9, and in order to adjustably secure the upper or telescopic tube 5 in position, said belt is provided with a split collar 10 encircling the tube 5, and adapted to be clamped in any desired position of adjustment by means of a clamping bolt 11.

It will be understood that the tubes 1 and 5 will be secured in position on the patient by means of the belts and will be telescopically adjusted as to length to suit the stature of such patient. In order to accommodate vertical adjustment of the arm from the shoulder joint, the upper end of the tube 5 is provided with a toothed rosette 12, which meshes with a similar rosette 13 formed on an end of an upper arm support tube 14, the angular adjustments between the two tubes to accommodate the position of the upper arm being secured by the co-operation of the toothed rosettes 12—13 and a clamp bolt 15 and wing nut 16, as will be readily understood.

The upper arm tubular support 14 is split for some distance adjacent its free end as at 17, and said end is formed with an enlarged portion 18 having a stop tooth 19 for a purpose which will hereinafter appear, and is also formed with a pair of ears 20 on opposite sides of the split portion 17 of the tube, said ears being engaged by a clamp bolt 21. The end of the tube may thus be contracted to apply clamping action on the end of a threaded tractor shaft 22 loosely telescoping within the tube 14. To maintain the threaded tractor shaft 22 against rotation when it is desired to change its 95 tractive adjustment, said shaft is formed with a longitudinal slot 23 engaged with an internal pin 24 carried by a rosette 25 equipped with teeth 26 for cooperation with the tooth 19 of the tube 14 in preventing rotation of the shaft, the shaft being ex-

tended or withdrawn by means of a threaded wing nut 27 on said shaft and in abutment with the face of the rosette 25. Under normal conditions after the shaft has been extended to the desired point, the clamp bolt 21 is operated to cause the end of the tube 14 to clamp the threaded end of the shaft to prevent accidental withdrawal movement of the parts, it being apparent that said 10 clamping pressure must be relieved when it is desired to change the position of the tractor shaft.

In order to sustain the forearm of the patient, the end of the shaft 22 is formed in 15 the shape of a toothed rosette 28 to cooperate with a similar toothed rosette 29 carried by the end of a tubular forearm shelf support 30. The rosettes 28-29 are pivotally mounted on a threaded clamp bolt 31 provided with a suitable wing nut 32 for clamping 20 the rosettes in the desired position of adjustment.

Shelf members 33 and 34 are provided for the upper and lower arms of the patient, respectively, and are of suitable contour to 25 properly receive the average arm which is taped or otherwise secured thereto, and each shelf is adjustable longitudinally and rotatively on its respective supporting tubes 14 and 30. Each shelf is held in any desired 30 position of adjustment on its support by means of split brackets 35 and 36, respectively, equipped with clamping bolts 37 and 38. In this connection it will be noted that 35 each of the shelves is pivotally mounted on its clamp bracket, said pivots being adjustable and held in any desired position by means of clamp bolts 39 and 40.

The outer end of the forearm shelf terminates in a flat portion 41 formed with a squared central opening for the reception of the squared shank of a clamp bolt 42 having a wing nut 43 which is adapted to detachably clamp in position a skeleton grip portion 44. The hand of the patient is passed through the opening in the skeleton grip and the fingers are secured in any suitable manner to the grip proper. In this connection it is to be noted that the grip is bifurcated as at 45 so that it may be placed in operative position as regards the bolt 43 without entirely unscrewing the bolt from the shelf.

When the forearm is secured with the 55 palm down or when it is desired to position the wrist in any special manner, such as the "cock-up" or "Bond's position," a grip support is employed comprising a plate member 46 formed with an adjusting slot 47 and a 60 palm plate 48, the latter being hinged as at 49 to the palm plate. The angular adjustment for the hand is secured by means of a link 50 pivoted at its opposite ends to the palm plate 48 and to a slide plate 51 formed 65 with a slot 52 for adjustable engagement

with the bolt 42, whereby the palm plate may be secured in any desired position, above or below the horizontal as indicated by the arrows in Figure 8. In order to provide means whereby a finger grip portion 53 70 may be adjusted angularly and in the same plane as the wrist, it is secured in position to the palm plate by means of a slotted portion 54 through which a clamp bolt 55 passes, said bolt also projecting through an 75 opening in the palm plate. It will be evident that the length of the hand support may be adjusted to suit the patient by means of the slots 47 and 54.

When it is desired to apply adhesive 80 traction to the upper arm, an L-shaped hitch support 56 is employed, having at one of its ends a rosette 57 which is bifurcated as at 58 for reception of the bolt 31. The rosette is formed on its 85 opposite faces with a plurality of teeth 59 for enmeshing with the teeth of the rosettes 28 and 29 and is interposed between said rosettes, the bifurcation 58 receiving the bolt 31. The outer or free end of the hitch support 56 carries a suitable slotted hitch frame 60 held in position by means of a clamp bolt 61, it being apparent that the frame may be rotated around the bolt and slid longitudinally as desired, and that said 90 frame forms a securing point for an adhesive traction member or band 62 secured to the upper arm of the patient, traction being obtained by operation of the wing nut 27 to extend the shaft 22.

If the fracture occurs adjacent the elbow joint and it is impossible or undesirable to apply adhesive traction to the upper arm, the forearm may be turned at right angles 100 to the upper arm and a pulling tractor member 63 slipped on the tube 30, said member being of suitable contour to press against the forearm (see Figure 4), and having a finger or stop member 64 in abutment with the rosette 29 to resist rotation of the member beyond a certain point. With this attachment it will be apparent that upon rotation of the wing nut 27 to extend the shaft 22, the member 63 through pressing on the forearm below the elbow will apply further 105 traction on the upper arm.

It is to be particularly pointed out in connection with this application, that means are provided (comprising slotted shaft 22, rosette 25 and tooth 19), whereby the upper arm may be rotated on its own axis, and that when this adjustment is desired the clamp 120 21 is loosened and the rosette 25 disengaged from the tooth 19, and then the entire forearm assembly bodily rotated with the tractor shaft as its axis until the desired adjustment is secured, when the rosette is again engaged with the tooth 19. The parts are thus locked 125 against rotation in either direction by the cooperation of the tooth 19, the rosette 25 130

and the slot and pin connection 23 and 24 between said rosette and the tractor shaft 22.

Under some circumstances it is desirable to employ the splint with a plaster cast, and 5 in order to supply means whereby the splint may be incorporated in the cast, the telescopic tubes 1 and 5 are removed and a short tube 64 equipped at one end with a rosette 65 for cooperation with the upper arm support tube rosette 13 is substituted. The end 10 of the tube 64 is encircled by a split clamping member 66 having a clamping bolt and wing nut 61 and carried by a plate 68, which in turn is embedded in the cast 69. The tube 15 64 is thus vertically adjustable to accommodate the stature of the patient and the other parts of the device operate in all respects as above described.

From the above description it will be apparent that I have produced a device of the character described which possesses all the features of advantage set forth as desirable; and while I have described and claimed the preferred embodiment of the same, I reserve 25 the right to make all changes properly falling within the spirit and scope of the appended claims.

I claim:

1. An arm splint comprising a main support 30 for securing to the body of a patient, an upper arm support carried by the main support and adjustable to swing horizontally and vertically with respect to said main support, a tractor member longitudinally and 35 rotatably adjustable around an axis coinciding with the axis of said upper arm support, a forearm support pivotally adjustable on the tractor member, shelves rotatively and longitudinally adjustable on the upper and 40 forearm supports respectively, and a hand-grip.

2. An arm splint comprising body belts, a telescopic main support secured to said body belts, an upper arm support carried by the 45 main support and adjustable to swing horizontally and vertically with respect to said main support, a tractor longitudinally and rotatably adjustable around an axis coinciding with the axis of said upper arm support, 50 a forearm support pivotally adjustable on the tractor member, shelves rotatively and longitudinally adjustable on the upper and forearm supports respectively, a hand-grip, and an adhesive hitch support detachably 55 carried at the pivotal point between the tractor member and the forearm support.

3. An arm splint comprising a main support 60 for securing to the body of a patient, an upper arm support carried by the main support and adjustable to swing horizontally and vertically with respect to said main support, a tractor member longitudinally and rotatably adjustable around an axis coinciding with the axis of said upper arm support, a

forearm support pivotally adjustable on the tractor member, shelves rotatably and longitudinally adjustable on the upper and forearm supports respectively, a hand-grip, and a tractor plate detachably carried by said forearm support.

4. An arm splint comprising a main support for securing to the body of a patient, a tubular upper arm support carried by the main support and adjustable to swing horizontally and vertically with respect to said main support, a tractor shaft adapted to telescope within said arm support, connections between said tractor shaft and arm support whereby said shaft may be adjusted longitudinally of the upper arm support or rotated around an axis coinciding with the axis of said support, a forearm support pivotally carried by said tractor shaft, and a hand-grip.

5. An arm splint comprising a main support for securing to the body of a patient, a tubular upper arm support carried by the main support and adjustable to swing horizontally and vertically with respect to said main support, a stop member projecting longitudinally from one end of said support, a tractor shaft adapted to telescope within said arm support, a wing nut on said shaft, a toothed washer interposed between said support stop member and adapted to engage the latter, means on said washer to engage the shaft to prevent rotation of the latter upon rotation of the wing nut, a forearm support pivotally carried by said tractor shaft, and a hand-grip.

6. In combination in an arm splint of upper and lower arm supports, toothed rosettes carried by the adjacent ends of said supports, a third rosette having teeth on its opposite faces interposed between said first-named rosettes, and a traction hitch member carried by said third rosette.

7. An arm splint comprising a main support adapted to be secured to the body of a patient, an upper arm support carried by said main support, a forearm support pivotally secured to one end of said upper arm support for angular adjustment and capable of bodily rotating around the longitudinal axis of the upper arm support as the center of rotation.

8. An arm splint comprising a main support adapted to be secured to the body of a patient, an upper arm support carried by said main support a forearm support longitudinally adjustable and pivoted to said upper arm support for angular adjustment and capable of bodily rotating around the longitudinal axis of the upper arm support as the center of rotation.

In witness whereof I hereunto affix my signature.

JOHN R. SIEBRANDT.
